UNITED STATES PATENT OFFICE.

JOHN PATRICK O'DONNELL, OF NEW MALDEN, COUNTY OF SURREY,
ENGLAND.

APPARATUS FOR WORKING RAILWAY SIGNALS AND SWITCHES.

SPECIFICATION forming part of Letters Patent No. 423,878, dated March 18, 1890.

Application filed September 23, 1889. Serial No. 324,846. (No model.) Patented in England December 15, 1888, No. 18,337.

To all whom it may concern:

Be it known that I, JOHN PATRICK O'DONNELL, a subject of the Queen of Great Britain, residing at Shoebury Villa, Penrith Road, 5 New Malden, in the county of Surrey, England, have invented certain new and useful Improvements in an Apparatus for Working Railway Signals and Switches, (for which I have obtained a patent in Great Britain, No. 10 18,337, bearing date December 15, 1888,) of which the following is a specification.

This invention has reference to apparatus for reducing the number of working-levers in the locking apparatus usually inclosed in 15 a signal-cabin; and it consists, first, in arrangements whereby one lever may perform the work usually performed by three levers, either by working three signals, or three points, or three facing-point locks and bars, 20 or three fouling or other bars.

It is usual at terminal stations, passenger-bays, sidings, burg yards, &c., to arrange for one "passenger-in" signal and one "shunt-in" signal from line—say K—to every road that 25 can be entered from line K, and a wrong-road shunt-out signal from the same roads—say E F G H to line K. It is also usual at the present time to provide a separate set of levers—say 1 2 3 4—to work the passenger-30 in signals from line K to roads E F G H, and a separate set of levers—say 5 6 7 8—to work the shunt-in signals from the same lever K to roads E F G H, and, again, a separate set of levers—say 9 10 11 12—to work 35 the shunt-out signals from the said roads E F G H to line K. It thus takes three sets of four levers, each set practically effecting the same interlocking, twelve levers in all. With this invention I effect the same result—40 viz., working the twelve signals with only four working signal-levers; but I provide in this instance a separate lever, which I term a "setting" or "king" lever.

I will describe my apparatus for effecting 45 my invention.

Figure 1 is a single-line sketch of a line of railway leading into four passenger or other bays or platforms. K is the one main line for entering these four bays E F G H. The 50 four-arm-semaphore stop-signal marked 1^a 2^a 3^a 4^a represents the four passenger stop-

signals for entering the four passenger-lines from line K. The four-arm shunt-disk signal marked 1^c 2^c 3^c 4^c represents the four in-shunt signals from line K into the platforms 55 E F G H. The four disk-signals 1^b 2^b 3^b 4^b represent the four shunt-out signals from lines E F G H, respectively, to line K.

Fig. 2 is a diagram showing the application of my apparatus to work the various signals, 60 hereinbefore described with reference to Fig. 1. In Fig. 2, 1^d 2^d 3^d 4^d 5^d represent the arms of the rocking shafts worked by levers 1 2 3 4 5, respectively. 1^m 2^m 3^m 4^m 5^m are a set of five rocking shafts, similar in design 65 and purpose to those commonly used in railway-signal work. As is well known, each of these shafts has two arms—for instance, in lever 1 the arm 1^d, previously referred to, and the arm 1^e, working the selector-bar. 70 Each of the levers 1 2 3 4 works in connection with one three-throw machine, the slide-bars of which are marked a b c, together with the number of the lever. The selector-bar of each is shown normally engaged with the middle 75 blade—that is, the B position. All the selector-bars 1^p 2^p 3^p 4^p have a bearing in and are actuated right and left by an actuating-bar, moved by setting-lever 5 through rocking shaft 5^m and cranks 5° 5^r. The crank or 80 rocking-shaft arm 5^d is attached to lever 5 by a downright connection, as in Fig. 5. The ends of the signal-blades of each three-throw machine are connected, respectively, a to passenger-semaphore-in signal, b to a shunt-out 85 signal, and c to a shunt-in signal. When the signal-man requires to signal a passenger-train—say, into platform G—he would move his setting-lever 5 into the A position, thereby actuating arms 5^d 5^o, rod 5^s, crank 5^r, and actuating-rod 5^t, thereby moving the selector-bars 1^p 2^p 3^p 4^p out of gear with blades 1^b 2^b 3^b 4^b, respectively, and into gear with signal-blades 1^a 2^a 3^a 4^a. Now, when he actuates his lever 2, which refers to platform G, the signal slide-bar 2^a would be drawn, thereby deflecting the third arm 2^a in the semaphore-post. Similarly, by moving the setting-lever to the C position, the selector-bars 1^p 2^p 3^p 4^p would be moved out of gear with blades 1^b 2^b 3^b 4^b and into gear with blades 1^c 2^c 3^c 4^c. Upon the signal-man again working any of 90 95 100

the levers 1 2 3 4, he would deflect a shunt-in signal—that is, one of the disks on the four-arm shunt-in disk part.

Fig. 3 is an enlarged plan view of the three-⁵ throw machine.

Fig. 4 is a sectional side view of Fig. 3, showing the relative heights and modes of engagement of the various blades.

Fig. 5 illustrates the three positions of the ¹⁰ setting-lever 5, the B or middle position being, preferably, the normal one. This, however, is entirely a matter of choice.

I do not bind myself to the precise method ¹⁵ shown of carrying the selector-bar—for instance, the top may be open and the selector-bar laid in instead of threaded through. It is obvious that the usual vertical and horizontal cranks may be substituted for the ²⁰ rocking shafts as the lead-off connection from the tail of the lever to the three-throw machine. In the particular example referred to I prefer to fix my machine as described, ²⁵ under the tails of the levers, or at any convenient position in the signal-box. If desired, however, it may be fixed at any suitable spot on the ground.

Although I have described a setting-lever as the means of actuating the selector-bar, as ³⁰ 1^p, into and out of gear with the signal-slide bars 1^a 1^b 1^c, yet I may sometimes make a point or other working lever perform this duty, or I may arrange for two other working-levers to actuate 1^p by means of cross-road connections, one actuating it from a middle position to the left, and the other from a ³⁵ middle position to the right, and vice versa.

My apparatus may be fixed on the ground adjacent to the facing and trailing points of a junction, especially a three-way junction, ⁴⁰ and may work the three-junction stop-signals in facing direction by one lever, and by the

point-levers, and the trailing stop-signals by another lever, and the corresponding distant in both directions by two more levers. This form of my apparatus is also suitably adapted ⁴⁵ for working siding-signals, and is, in short, intended to act where any three or more separate performances are required, only one of which can be performed at a time with safety.

What I claim is—

1. The combination, with three parallel signal-operating bars, such as 1^a 1^b 1^c, of a selector-bar, such as 1^p, arranged substantially parallel with the said three bars, normally connected to one of them and adapted ⁵⁵ to move it longitudinally, and a transverse sliding bar 5^t, engaging with the said selector-bar and adapted to move it out of connection with the bar with which it normally engages and connect it in a similar manner with either ⁶⁰ of the two remaining bars, substantially as and for the purpose set forth.

2. The combination, with the three parallel signal-operating bars 1^a 1^b 1^c, of the selector-bar 1^p, arranged substantially parallel with ⁶⁵ the said three bars, and normally connected to the middle bar, the rock-shaft provided with the arm 1^d and an arm 1^e, connected to the selector-bar for moving it and the signal-bar connected to it longitudinally, the transverse bar 5^t, engaging with the said selector-bar, and the hand-lever operatively connected to said transverse bar, whereby the selector-bar may be slid transversely out of ⁷⁰ connection with the said middle bar and connected in a similar manner to either of the two remaining bars, substantially as and for the purpose set forth.

JOHN PATRICK O'DONNELL.
